WALL-MOUNTABLE RACK FOR PERSONAL ACCESSORY ITEMS

Edward J. Belkin and Esta L. Belkin, both of 6600 Etiwanda Ave., Reseda, Calif.

Filed May 29, 1961, Ser. No. 65,380

Term of patent 14 years

(Cl. D4—3)

FIG. 1

FIG. 3

FIG. 2

FIG. 4

FIG. 5

The dominant features of our design reside in those portions shown in full lines on the drawing.

We claim:

The ornamental design for a wall-mountable rack for personal accessory items, substantially as shown and described.
